ELBERT PEETS, OF CLEVELAND, OHIO.

TREE SURGERY.

1,100,396.

Specification of Letters Patent. Patented June 16, 1914.

Application filed March 28, 1913. Serial No. 757,366.

To all whom it may concern:

Be it known that I, ELBERT PEETS, citizen of the United States, residing at Cleveland, in the county of Cuyahoga and State of Ohio, have invented certain new and useful Improvements in Tree Surgery, of which the following is a specification.

This invention relates to tree surgery, and the invention consists in the new and original means employed for filling a cavity or wound in the trunk or branch of a tree, substantially as shown and described and particularly pointed out in the claims.

In the accompanying drawings, Figure 1 is a vertical sectional elevation of a trunk of a tree having a cavity filled according to my invention, and Fig. 2 is a front view of Fig. 1. Fig. 3 is a sectional elevation of a portion of the tree and facing shown say 20 as seen in Fig. 2, the same being enlarged and disclosing particularly the matter of securing the briquets in place. Fig. 4 is a cross section of Fig. 2, and Fig. 5 is a cross section corresponding to Fig. 4 but showing 25 a modification in the manner of fastening the briquets in place.

Considering, first, the state of the art and the observations and experiences which have led up to the present invention, it is to be understood that the desideratum has been to get a filling which will flex with the tree and thus avoid the cracking or splitting which generally attends a perfectly rigid and inflexible filling. Of this latter kind 35 the cement filling is the most common.

With the recognition of the fact that cement is not fitted to serve as a filling material for every kind of cavity, has come a demand for a more elastic material, more 40 like wood in its properties and capable of becoming more nearly like an integral part of the tree. The moment this need was discovered asphalt suggested itself as the material which would most nearly meet the 45 requirements. Its eminent fitness is obvious. It is slightly elastic, while concrete is absolutely rigid; it is waterproof, while concrete absorbs water; it adheres to wood while concrete does not; it is light and 50 warm, while concrete is heavy and cold. It is hard enough to stay in place and to resist the force of the ingrowing callus.

The only reason why asphalt has not long since superseded concrete to a large degree is that until lately no method of handling it

economically and effectively has been worked out. The means most commonly practised is to form a dam of some such material as clay over the mouth of the wound and to pour the melted asphalt in behind it. This, 50 however, is open to the objection that the solid material is rather expensive, and that a dam of any considerable height is difficult to build up. Mixing the asphalt with sand and re-heating it in place, as is done 55 in laying asphalt pavement, is a difficult and very slow process. I have, therefore, conceived and developed the present invention which consists, broadly, in a wall or filling on the face of the cavity, consisting 60 of briquets *b* made of excelsior and sawdust or their equivalent, bound together with asphalt or other elastic cementitious material. The wall is built up only in the front part of the cavity and the briquets 65 are cemented together with melted asphalt. To prevent the possibility of a crank opening between the filling and the wood, as invariably occurs with concrete, the briquets 70 next to the wood are secured thereto by 75 means of nails *n*. The wall of briquets is reinforced by braces and wires *w* from the back of the cavity and in other ways as may be seen best mechanically. The remainder 80 of the cavity, back of the front wall, is filled 85 with any one of a number of materials *f*, such as asphalt staff, sawdust, cinders or other materials as may be available and suitable.

The preparation of the cavity for an asphalt briquet filling is not essentially unlike the preparation for a filling of concrete. The decay must all come out, of course, in either case, but the asphalt often requires less cutting away of sound wood than does 90 the preparation for concrete. The reason for this is that it is usually essential to make the cavity wedge-shape, if it is to be 95 filled with concrete, thus making the mouth the narrowest part of the cavity. The idea 100 is to prevent the filling or any part of it from working out of the cavity. In the case of asphalt this danger is much less and can be met in other ways. There is no 105 change, however, in the rules as to the handling of the cambium and the shaping of the incision in order to facilitate the growth of the callus over the filling. The interior must receive a dressing *d* just as for concrete. A hot mixture of asphalt and raw 110

linseed is the best for the purpose, because it stays sticky for some time. Previous, however to the application of this dressing, such braces must be put in as are necessary, 5 and a method of reinforcing or bracing the briquet wall must be decided on and provided for. Two different ways in which the wall can be strengthened are shown in the accompanying drawings and any equivalent 10 thereof may be used, as hereinafter described.

If the cavity is a basal one and extends below the ground, the lower part up to the surface of the soil, or two or three inches 15 above it, must be filled with concrete *c*, or partly with cinders or the like. When the concrete is hard the work of filling with asphalt begins. Paint the upper surface of the concrete, which has been leveled off, 20 with asphalt. Have a kettle of melted asphalt just as near the cavity as is possible without risk of the heat from the fire damaging the tree or the filling. Drive a nail nearly through one of the briquets near its 25 end. Spear the briquet with an awl and dip it into the hot asphalt. Lay it alongside the wood with its outer edge about quarter of an inch back from the cambium. Drive in the nail and pull out the awl. If 30 a considerable part of the briquet lies against the wood no further work in relation to it is necessary. If, however, a wedge-shaped space remains between the back part of the briquet and the wood, it had better be filled 35 up with a mixture of about equal parts of asphalt and sawdust. Set a similar briquet against the wood on the other side of the cavity. Now you can fill in between the two briquets in place. Take a briquet on the awl, 40 dip it, and place it on its longer side on the concrete, its front being flush with the first briquet and with the edge of the concrete. It is probable that this first flat briquet will have to be cut to a roughly triangular shape 45 in order to bring its front up to the edge of the concrete. Lay another briquet beside the first and continue the course over to the other side of the cavity. Lay on two more courses in the same way. This will bring 50 the flat courses up to a level with the top of the briquet nailed to the wood at the sides of the cavity. Start the next course by laying a briquet with its narrow edge against the wood. Nail this briquet to the wood 55 and to the briquet below it. Finish the course. Then, at each side, nail a briquet flat against the wood at each side. Build the wall up between them, lay another course from wood to wood, and so on. This process 60 is more complicated, naturally, when the side of the cavity is slanting or curved. The principal difference is that the soft asphalt-sawdust mixture is more often called on to fill crevices and corners. The necessary care required for fixing the briquet at 65

the edges of the wall to the wood depends upon the degree of probability there is that a crack will open up between the filling and the wood. If the briquets at the side are tightly nailed to the wood, when the tree 70 sways the enlargement of the mouth of the cavity will be taken up by the elasticity of the briquet wall. If none of the briquets are nailed to the wood, a crack may appear, under certain circumstances, along the 75 edge of the filling.

The method above described of securely fixing the filling (or the front wall of the filling, in case the wall-and-back-filling method is used) to the wood forming the 80 sides of the cavity, is the most useful of several which might be employed. Obviously, if so desired, all the briquets contiguous to the wood can be laid with their long sides against the wood, instead of laying 85 half of them with the small end against it.

In carrying up the wall it is well to keep its face as smooth as possible, particularly at the sides, but it is not difficult to smooth the surface with a hammer, or to cut off 90 projections with a chisel, after the wall is finished. At intervals, as it is built up, the wall will need bracing. The amount of bracing required depends principally upon the width of the wall. If it is not more 95 than a foot wide, no bracing will ordinarily be needed. There are two types of braces, those which prevent the wall from bulging out and those which prevent it from caving in. The first function is best performed 100 by the wire braces *w* and the second by pieces of wood *g* and *h* set in crossed relation in the cavity, as in Fig. 5. There are two good ways of handling the wire. The most obvious plan is to drive some staples *s* into 105 the back of the cavity and run short lengths of wire from them to the wall. The easiest way is to employ V's of wire having the ends bent down at right angles. One limb 110 of the V-shaped wire is threaded through the staple and the bent ends are driven into the briquets. One of these V's is put into every second or third course. Another way 115 is to use the same kind of V's, but to anchor them, not to staples, but to a strong wire *x* run from one end of the cavity to the other from bolts or pieces of wood across its top and bottom. The advantage in this last plan is that greater elasticity is permitted to the 120 wall without loss of strength. It must not be supposed, however, that the asphalt wall is of itself weak. On the contrary, it is very strong, but the conditions surrounding work in trees are so extremely trying that 125 braces which may never be called on to undergo an ounce of strain, ought to be put in, if only by way of precaution. The filling *f* in the space back of the wall is to form a backing for the wall, helping to hold it in place. The filling also helps in putting 130

in some types of braces and it holds them in place. On the whole, I am inclined to consider coal ashes or fine cinders the best material for filling the space back of the briquet wall on account of their packing qualities, their cheapness, and the fact that they need no treatment to make them proof against insects and decay. Sawdust does very well, but it must be treated with carbolineum before it is used. An easy way to do this is to spread it out in a large box, sprinkle it with carbolineum from an ordinary sprinkling can, then turn it over and sprinkle it again. All the sawdust does not have to be saturated, a gallon of carbolineum to ten or fifteen cubic feet of sawdust will be enough. Excelsior, also treated with carbolineum does very well, especially for very thin fillings.

The back-filling should be carried up along with the briquet wall, and it should be thoroughly pressed or tamped into place in order to prevent subsequent settling. If it is felt that these materials would not give a sufficiently stable backing for the wall the entire filling can be made of briquets, of hot asphalt-sawdust mixture, of asphalt-staff, or of ordinary staff made of excelsior and plaster of Paris. Or, a compromise between the loose and solid fillings can be made by putting in, every two or three feet, a section, say three courses thick, of solid briquets, the remainder of the filling being of the wall-and-back-filling type.

In large cavities, especially when sawdust is used as a back-filler, it is well to provide for the ventilation of the filling. The best way to do this is to leave out a briquet near the bottom of the wall and another near the top, as indicated by 2 and 3. The holes thus formed must be provided with a netting to keep the sawdust in and insects out. The face of the wall for an inch or two around the opening can be painted with hot asphalt and a piece of copper or brass netting can be pressed against the opening and held there until the hardening asphalt cements it in place.

The surface of a filling made in accordance with these specifications for the asphalt-wood briquet system is likely to be rather irregular, but is not likely to be irregular enough to interfere with the growth of the calluses, yet it may be desirable, from the aesthetic standpoint, to make it smoother. It is not difficult, with a broad sharp chisel or gouge, frequently dipped in oil, to cut away the corners of projecting briquets. Then the surface can be warmed with a gasoline torch, not held too near, and irregular places can be pounded down with a mallet. Finally, the entire surface must be given a heavy coat of hot asphalt to which about one-fifth of its bulk of raw linseed has been added. Or,

as a modification of this coat or cover I may employ an elastic fabric covered over the entire face of the filling in order to give the filling a smoother surface and to prevent the entrance of water into any cracks which might form in the filling. Such a covering is practically impossible on concrete, because there is no satisfactory way of fixing the covering to the filling, and the covering cannot be made to bridge the most important crack, the one which appears between the wood and the filling. With a filling of asphalt briquets, on the contrary, it will be easy to nail and cement the covering to the filling at every point, and the fact that no crack can appear along the edge of the filling, makes it possible for the covering to effectively cover every crack that can occur.

In the building-up of my improved filling, it is to be especially noticed that I begin building my filling in the cavity immediately at the edge of the cavity all around and nail the edge bricks or pieces to the said wall, care being taken to employ sufficient cement to make the joints perfectly tight and thus prevent any possible cracking or breaking away of the wall at the edge of the cavity from extending inward into the body of the wall. Whatever will best safeguard this danger point in the construction may be adopted, and I have found the use of a special edging of asphalted felt or the like of suitable thickness and mechanically affixed to the tree a good precautionary medium. The body of the filling comes between these newly made edges which constitute the initial portion of the filling and become homogeneous therewith, as in the case where the briquets come directly against the wall of the cavity.

What I claim is:

1. Means for treating cavities in trees consisting of elastic units constituting an outer wall and conforming to the contour of the tree about said cavity.

2. In means for mending trees having cavities, a filling comprising a wall of briquets made of a flexible material and permanently affixed to the inner edge portion of the said cavity and to each other and substantially flush outside with the exterior of the tree.

3. The means herein described for filling a cavity in a tree consisting in an adhesive substance applied to the wall of the said cavity and a wall of asphalt briquets built into said cavity and adhered to the wall thereof and to each other.

4. A filling for cavities in trees comprising a wall consisting of flexible units built together across the cavity and anchoring means engaging said wall with the wall of the cavity.

5. A tree filling for a cavity in a tree

consisting of a flexible wall occupying the front of said cavity and a dry filler packed into said cavity behind said wall.

6. A filling for a cavity in a tree consisting of a flexible wall built into the front of said cavity and a coating over said wall as a surface finish therefor and a dry filler packed behind said wall and filling said cavity.

10 7. A filler for a cavity in a tree comprising a wall of briquets and a water proofing and surface evening coating spread upon the outside of said wall.

8. A filling for a cavity in a tree having 15 ventilating openings at the bottom and top thereof open to the outer air.

9. A filling for a cavity in a tree having an outer wall of superposed units extending across the entire front of said cavity

said wall having its edge units secured to 20 the tree at the edges of the cavity.

10. In a tree having a cavity, and a filling for the cavity consisting of a homogeneous wall provided with a separately secured edge portion all around nailed and 25 cemented to the edge of the cavity and having the remaining portion of said wall built into said edge portion.

11. A filling for a cavity in a tree comprising a wall composed of flexible units 30 and metallic stays at intervals engaging said wall with the wall of said cavity.

In testimony whereof I affix my signature in presence of two witnesses.

ELBERT PEETS.
